MECHANICAL BURGLAR ALARM

Filed April 28, 1938

UNITED STATES PATENT OFFICE

2,196,961

MECHANICAL BURGLAR ALARM

Harry Epstein, Johnstown, Pa.

Application April 28, 1938, Serial No. 204,875

3 Claims. (Cl. 116—87)

It is the purport of the present invention to provide a simple and inexpensive burglar alarm which may be vended within the price range of the average householder and is especially adapted for use on doors and windows of houses or other buildings.

Principal objects of the invention are to provide a small inexpensive alarm device capable of facile attachment to windows, doors and the like; to provide a purely mechanical alarm automatic in its operation when a window or door, with which it is attached, is opened; and to provide an audible signal wholly mounted on the inside of the door or window and capable of rapid engagement and disengagement and positively operable without possibility of injury or damage to person or property.

Other objects of the invention will be apparent from the following description of the present preferred form of the invention, wherein:

Fig. 1 is a front elevational view of an alarm constructed in accordance with the present invention, illustrating the application of the same on a window and window frame,

Fig. 2 is a front elevational view of the alarm casing, portions thereof being broken away to disclose details,

Fig. 3 is a longitudinal sectional view of the alarm casing taken centrally through the latter and illustrating the application of the alarm,

Fig. 4 is a transverse sectional view taken through the casing on line 4—4 of Fig. 2 looking in the direction of the arrows,

Fig. 5 is a longitudinal sectional view of the casing showing the position of the parts after the alarm has been sprung or operated,

Fig. 6 is a rear elevational view of the alarm casing, and

Fig. 7 is a perspective view of the alarm release.

To illustrate the application of my invention, I have, in Fig. 1, illustrated a portion of a window casing 8 and window 9. The alarm of my invention is, as illustrated in Fig. 1, attached to the sash of the window and operatively connected 45 with the sill of the window frame.

Preferably, the alarm consists of a casing 10 formed of metal or other suitable material, the casing being preferably of rectangular shape and relatively flat so as to occupy a minimum amount 50 of space when in use. The casing may be stamped from a sheet and provided with bayonet slots 11 through which latter nails 12 or other supporting means may be engaged.

The casing is equipped with suitable detonating mechanism which may consist of a spring

pressed hammer 13 hingedly mounted, as indicated at 14, midway the ends of the casing. The hammer complements and is adapted for engagement with a detonating cap holder 15. The manner of mounting the cap in the holder is illustrated to advantage in Figs. 3 and 5, wherein the cap is illustrated at 16. Preferably, the cap container 15 is mounted in the casing adjacent one end of the latter, the opposite end of the casing being adapted to receive the hammer when 10 the latter is in a cocked or set position, as shown in Fig. 2 of the drawing. The container 15 may be fixed from displacement by forming tabs 17 on opposite sides of the container, the tabs extending through openings 18 formed in the bottom wall of the container, as illustrated to advantage in Fig. 4.

The container is also provided with a cover or lid 19, one end of which is preferably pivotally mounted, as indicated at 20, in one end of the 20 container, this being the end opposite to that in which the cap holding container 15 is mounted. The cover or lid 19 is designed and utilized for the purpose of holding the hammer in a cocked 25 or set position, as the cover extends over the detonating mechanism mounted in the casing. The lid 19 may be held from casual movement by suitable means, generally designated 21, consisting of a bar one end of which is slidably mounted in a loop 22, the latter being formed in 30 the bottom wall of the casing 10, as shown to advantage in Fig. 6. The opposite end of said bar is formed to provide a yoke 23 which slides over the free end of the lid 19.

To set the alarm, the hammer 13 is operated 35 into a cocked or set position and the lid 19 closed into engagement therewith, pursuant to which the yoke 23 is slid into a position overhanging the free end of the lid. The alarm is sounded by disengaging the yoke end of the 40 means 21 from the free end of the lid 19 permitting the latter to be thrown into an open position, as shown in Fig. 5 of the drawing, under the uncoiling action of the spring pressed hammer 13. The hammer, as also shown in 45 Fig. 5 of the drawing, continues in its movement so as to contact the cap 16 causing explosion of the latter. For the purpose of disengaging the yoke end 23 of the releasing bar 50 from the lid or closure 19, any suitable means may be employed. In the drawing, I have shown a cable 24, one end of which is secured to the means 21, which has been referred to above as the releasing bar, the opposite end of the cable 55

being anchored to a hook 25 or the like which is engaged with the sill of the window frame 8.

In operation, it is manifest that when the window is moved into an open position, the releasing bar is caused to be disengaged from the lid 19 permitting the detonating mechanism to operate in a manner already described. It is, of course, to be understood that although I have described the invention as being particularly adapted for use on windows, nevertheless it is susceptible of a variety of uses. Furthermore, it is to be understood that various changes may be made especially in the details of construction, proportion and arrangement of parts within the scope of the claims hereto appended.

What is claimed is:

1. An alarm device including a casing, detonating mechanism mounted in said casing including a spring-pressed releasable hammer and a cap carrying container in the path of said hammer when the latter is released, a lid movably mounted on said casing and engageable over said detonating mechanism, to hold the hammer of the detonator in a cocked position, and means to secure said lid from movement, said means being operable to release the lid under pressure of the hammer and to permit said hammer when released to contact the cap carried in said container.

2. A burglar alarm for attachment to the closure of a house, comprising a casing engageable with the house closure, a part of the casing being movable, detonating mechanism mounted in the casing, a part of the detonating mechanism being movable and adapted to co-act with the movable part of the casing, and means movable carried by the casing and engageable with the movable part of the latter to secure the movable part of the detonating mechanism from operation, said means being anchored to a fixed part of the house, adjacent the closure, whereby opening of the closure actuates the said means to effect release of the movable casing part and detonating parts.

3. In combination with a closure frame and a closure movably mounted in the latter, a casing contained detonator carried by the closure, a part of the casing forming a lid and being movable and arranged to hold the detonator inoperative, and release means mounted on said casing and engageable with said lid, the release means being operable upon movement of the closure, to effect disengagement of said release means from said lid, whereby the lid moves free of the detonator to permit operation of the detonator.

HARRY EPSTEIN.
